UNITED STATES PATENT OFFICE.

JOHN ROWBOTHAM, OF PHILADELPHIA, PENNSYLVANIA.

ROTARY WATER-METER.

SPECIFICATION forming part of Letters Patent No. 325,362, dated September 1, 1885.

Application filed March 13, 1885. (Model.)

To all whom it may concern:

Be it known that I, JOHN ROWBOTHAM, a citizen of the United States, and a resident of Philadelphia, Pennsylvania, have invented 5 certain Improvements in Water-Meters, of which the following is a specification.

My invention relates in general to a class of water-measuring devices to be applied to pipes, in which the working-chamber of a casing inclosing a drum provided with two diametrically right angular rigid sliding vanes is provided with two concentric surfaces, of which the upper is a bearing for the peripheral surface of the drum, and the lower, which 15 is of greater radius than the upper, bounds a measuring-surface—in which the said concentric surfaces are connected by eccentric or cam surfaces—and in which two water-ports, respectively forming the entrance and exit 20 for the water, open into said eccentric surfaces.

In meters of the above class it is a desideratum not only that the water should be caused to pass through the meter in as nearly as possible a straight line, so that its flow be not retarded by the friction and changes of course incident to long and tortuous passages, but it is also of prime importance that the vanes during the period of their sliding over or being acted upon by the cam-surfaces should move as freely—that is to say, with as little frictional contact against or straining with respect either to said camways or to their slotted ways or slide-bearings in the drum—as is 35 possible, so that the vane-provided drum may be extremely sensitive under a small head or pressure of water, and, if desired, in connection with a discharge-orifice of small diameter or when supplying a small stream. It is, 40 moreover, a most essential requirement that the vane-provided drum should be capable of being rotated backward or in the opposite direction to that of its usual rotation, because in many instances, when the inlet-pipe becomes 45 clogged with matter too large to pass either through it or through the meter, it becomes essential to be able to clear said pipe by steam, water, or other pressure applied to the outlet-pipe and exerted backward through 50 said outlet-pipe and through the meter into the inlet-pipe. Heretofore, however, in meters of the foregoing class, in which the

drums have been provided with sliding vanes, the inlet and outlet ports have occupied relatively such positions that while the water in 55 passing through the working-chamber may have had access at the same time to both sides of both of the acting extremities of the vanes, so that the said vanes have been under an equilibrated pressure and the drum acutely 60 sensitive, it yet has been retarded or rendered sluggish of flow by being caused either to travel completely around the circumference of the working-chamber in a circuitous or spiral course, or else to travel around said circumference in an arc equal to three-fourths of its full extent, and largely greater than the length of what is in fact the necessary measuring-surface of said chamber, while, so far as my knowledge extends, it never has been the 70 practice in meters having sliding vanes traveling in contact with the measuring-segment, and in which the ports have been so introduced to the working-chamber that the water has traveled through it in a short, direct, 75 comparatively straight, and consequently unretarded course, to provide any means for also securing access of the water to both sides of both the, for the time being, advancing and receding vanes of the drum during their traverse of the cam-surfaces, so that said vanes may during such traverse be under an equilibrated pressure and the sensitiveness of the instrument for accurate measurement be thereby and in consequence thereof preserved. 85

I have discovered that the admitted advantages, first, of the introduction to and exit of the water from the working-chamber preferably in the same straight line, and through a short segmental course throughout the length 90 of and in contact with the segmental floor of which the vanes travel, and, second, of an equilibrated pressure of the water upon both sides of both the advancing and retreating vanes during their traverse of the camways, 95 can both be at the same time and in the same meter secured by a particular construction and arrangement of the inlet and outlet ports with respect to a short and direct segmental measuring-surface, and to the camways of the working-chamber, and also by the provision in conjunction both with said inlet and outlet ports, and with said camways, of chambers or recesses at least coextensive in length with 100

the length of said camways, and I have represented in the accompanying drawings and described in this specification a good form of a convenient embodiment of my said improvements, (in connection with other improvements relating to the vanes of the drum,) the particular subject-matter which I claim as novel being hereinafter definitely specified.

In the accompanying drawings I have shown my improvements as applied to a water-meter of the construction illustrated and described in an application for patent filed by me December 1, 1884, Serial No. 149,203.

In these drawings, Figure 1 is a side view of the meter with my improvements, but having the cover-plate detached; Fig. 2, a sectional plan on the line 1 2, Fig. 1; Fig. 3, a sectional perspective of the drum with its blades; Fig. 4, a sectional view of one-half of the meter on the line 3 4, Fig. 2; and Fig. 5 is a sectional view on the line 5 6, Fig. 1, with the drum and its vanes removed.

The casing A is preferably of the circular form shown in Fig. 1, and is provided with an inlet, *a*, and outlet *a'*, preferably in line with each other. One end of the casing is closed, while the other is provided with a detachable cover-plate, A', as shown in Fig. 2. The closed end of the casing carries the box C, containing the registering mechanism, which may be of any suitable construction, this box being preferably cast in one with the casing A.

The cylindrical portion of the casing is provided with a filling-piece, G, as described in my above-cited application, so as to form a working-chamber having two faces, *x y* and *v w*, concentric with the axis of the rotary drum, hereinafter described, while the intermediate faces, *w x* and *y v*, are eccentric thereto.

The rotary drum D, I prefer to construct, as described in my above-cited application, with central journals, *d d'*, one adapted to a bearing in the cap, and the other adapted to a bearing in the closed end of the casing. An extension of the latter journal is provided with a worm, *q*, engaging with a wheel, *p*, of the registering mechanism.

The drum D is provided with the usual transverse slots, to which are adapted the sliding vanes E E', each in itself rigid, as distinguished from that class of vanes which are made of two parts, with an intermediate spring or springs to extend them. The drum is so mounted in its bearings that its periphery will move in contact with the concentric face *w v*, while the ends of the vanes E E' as they are successively projected from the drum travel in contact with the other and longer face, *x y*, which may be termed the "measuring-surface."

In my above-described application each of these vanes is shown and described as being equal in length to the diameter of the working-chamber; but such a construction is attended with the objection that if any solid

matter should get between the end of an advancing vane and the lower edge of the inlet-opening *a*, Fig. 4, the meter would cease to operate. To meet this difficulty I make the vanes, as shown in Fig. 1, somewhat shorter in length than the diameter of the working-chamber, so that if any solid matter should get in between an advancing blade and the edge of the inlet-opening the clearance left at the opposite end of the blade will allow the latter to yield and the drum to continue its rotation, the solid matter being allowed to pass through the meter and escape without arresting the operation of the meter.

As the blades are shorter than the diameter of the working-chamber, the eccentric surface *y v* cannot be relied on entirely to push the vanes outward at the opposite side to the full extent to insure their always coming into contact with the measuring-surface from *x* to *y*. This is insured, however, by centrifugal force when the meter is operating at a relatively high speed, and on the other hand by gravity when the drum rotates slowly. I therefore always place the measuring-surface *x y* below, in order to attain this gravitating action in connection with the shortened vanes.

In order that the meter may continue to work, no matter if the vanes become shortened by wear at the ends, I make the notches *s* therein, Fig. 3, considerably wider than the extent of movement of the vanes, and preferably the widths of the notches are about double the extent of movement, so that the legs *e* of one vane, Fig. 3, will not come into contact with the transverse portion of the other vane, and thereby prevent the outer end of the vane from coming into contact with the wall of the working-chamber.

In order to have the pressure on the vanes equalized during their sliding action, and so lessen the friction against the slots in the drum, I provide in the walls of the working-chamber recesses *k*, which extend at least throughout the length of its eccentric surfaces *w x* and *y v*, as shown in Figs. 1, 2, and 4, so that the water will have access to both sides of both the advancing and receding blade, and there will be no lateral pressure thereon during their entire sliding motion.

Such being a description of a device conveniently embodying my invention, it is proper for me to add that while the best operation of a meter of this class is secured by applying the ports in a horizontal position on opposite sides of the casing and in alignment, as shown in the drawings, yet I do not restrict myself to placing them exactly opposite to each other, or to introducing them to the casing in a strictly horizontal disposition or upon a common level, because so long as they communicate with the recesses in the cam-surfaces and are introduced upon opposite sides of the vertical axis of the casing, all the advantages flowing from the provision of recessed camways in communication with said ports are secured; and I therefore in the claims

employ the words "horizontally-disposed opposite ports" under the foregoing qualifications.

I claim as my invention—

- 5 1. The combination of the casing and rotary drum of a water-meter with transverse rigid vanes carried by the drum, and shorter in length than the diameter of the chamber in which they move, substantially as set forth.
- 10 2. The combination of the casing and rotary drum of a water-meter with transverse rigid vanes carried by said drum, the said vanes being shorter in length than the diameter of the chamber in which they move, and
- 15 crossing each other, and having notches considerably greater in width than the extent of motion of the vanes, as set forth.
- 20 3. A water-meter consisting of a casing having a working-chamber with eccentric surfaces wx and vy and concentric surfaces wv and xy , with the measuring-surface xy at the bottom, and a rotary drum carrying rigid vanes shorter than the diameter of the working-chamber, as and for the purpose set forth.
- 25 4. A casing for the vane-provided drum of a water-meter, the working-chamber of which is provided with an upper segmental surface, being a bearing for the peripheral face of the drum, with a lower segmental measuring-surface concentric with said upper surface, but
- 30 of greater radius, and with two intermediate eccentric surfaces or camways, each provided

with a recess at least coextensive with its length, and likewise provided with horizontally-disposed opposite ports opening into 35 said recesses, substantially as and for the purposes set forth.

5. In a meter, the combination of a drum having sliding vanes and capable of rotation in either direction, with a casing the working-chamber of which is provided with an upper segmental surface, being a bearing for the peripheral face of said drum, with a lower segmental measuring-surface concentric with said upper surface, but of greater radius, and with 45 two intermediate eccentric surfaces or camways, each provided with a recess at least coextensive with its length, and likewise provided with horizontally-disposed opposite ports opening into 50 said recesses, the arrangement being such that while the water enters and leaves the meter upon opposite sides and passes through it in a short segmental course, so as not to be retarded, the vanes during their passage over the camways are under an 55 equilibrated pressure of water in the recesses, substantially as and for the purposes set forth.

In testimony whereof I have signed my name to this specification in the presence of two subscribing witnesses.

JOHN ROWBOTHAM.
